US00D481703S

(12) **United States Design Patent** (10) Patent No.: **US D481,703 S**
Togawa et al. (45) Date of Patent: ** Nov. 4, 2003

(54) **RADIO RECEIVER FOR CARS**

Primary Examiner—Prabhakar Deshmukh

(75) Inventors: **Shinichi Togawa**, Kyoto (JP); **Yasuhide Tanaka**, Kyoto (JP); **Katsuji Matsushita**, Kyoto (JP)

(74) Attorney, Agent, or Firm—Dickstein Shapiro Morin & Oshinsky LLP

(73) Assignee: **Omron Corporation**, Kyoto (JP)

(57) **CLAIM**

(**) Term: **14 Years**

The ornamental design for a radio receiver for cars, as shown and described.

(21) Appl. No.: **29/156,744**

DESCRIPTION

(22) Filed: **Mar. 7, 2002**

FIG. 1 is a front view showing my new design for a radio receiver for cars;

(30) **Foreign Application Priority Data**

FIG. 2 is a rear view of the radio receiver for cars of FIG. 1;

Oct. 12, 2001 (JP) 2001-030057

FIG. 3 is a right side view of the radio receiver for cars of FIG. 1;

(51) LOC (7) Cl. **14-03**

FIG. 4 is a left side view of the radio receiver for cars of FIG. 1;

(52) U.S. Cl. **D14/157**

FIG. 5 is a top view of the radio receiver for cars of FIG. 1;

(58) **Field of Search** D14/156, 157,

FIG. 6 is a bottom view of the radio receiver for cars of FIG. 1;

D14/160, 162, 164, 168, 188, 197, 198,

FIG. 7 is a perspective view of the radio receiver for cars of FIG. 1;

225, 226, 257, 258, 265; 369/75.1, 75.2,

FIG. 8 is a second perspective view of the radio receiver for cars of FIG. 1;

77.1, 77.2; 455/844, 347, 348, 350, 351

FIG. 9 is a third perspective view of the radio receiver for cars of FIG. 1; and,

(56) **References Cited**

FIG. 10 is a reference perspective view showing a state of use of the radio receiver for cars of FIG. 1.
